AUGUSTUS HENRY TAIT, OF JERSEY CITY, NEW JERSEY.

Letters Patent No. 96,997, dated November 16, 1869.

IMPROVEMENT IN STILLS FOR DISTILLING NAPHTHA AND PETROLEUM.

The Schedule referred to in these Letters Patent and making part of the same.

To all whom it may concern:

Be it known that I, AUGUSTUS HENRY TAIT, of Jersey City, in the county of Hudson, and State of New Jersey, have invented a new and useful Improvement in Stills for Distillation of Naphtha and Petroleum; and I do hereby declare the following to be a full, clear, and exact description thereof, which will enable those skilled in the art to make and use the same, reference being had to the accompanying drawing, forming part of this specification, in which drawing—

Figure 1 is an elevation of a vertical longitudinal section of my invention.

Figure 2 is a plan.

Similar letters indicate corresponding parts.

This invention relates to the distillation of naphtha from petroleum, and to the distillation of petroleum; and

It consists in a supplementary or ascending worm, and a condenser, placed over the still proper, up to or into which ascends all the vapors that are generated, and, where they become separated into light and heavy vapors, the heavy vapors falling back into the still, leaving the lighter vapors in the worm or supplementary condenser, whence they pass into a second condensing-apparatus, where they are finally condensed, the naphtha or light oils formed from them being gathered into a suitable receiver.

The ascending worm and condenser are so arranged and combined with the still proper and its ordinary condensing-apparatus as to be capable of being disconnected therefrom, so that after the lighter vapors have been separated, the heavier vapors can next be condensed in the ordinary condensing-apparatus, by which arrangement I am able, by a continued and uninterrupted process, to separate the constituents of the lighter and medium oils from those of the heavier, and to condense and collect the naphtha and illuminating-oils separately from each other.

The letter A designates the still proper, which receives the charge of crude petroleum. It is heated by means of steam, which is admitted into it through a steam-pipe, B, and also, whenever preferred, by means of a furnace beneath it.

The vapors from the charge pass off through the pipe C, answering the usual purpose of a gooseneck, and are conducted through the pipe C into the worm E, which is arranged in the condensing-tank D. This tank is supplied with water, or other condensing-medium, at a suitable temperature, to allow the constituents of the lighter oils or liquids, such as naphtha,

to pass over and upward through the worm E, and out of its top into the pipe F, and to prevent the constituents of the heavier oils from entering or remaining in the worm E. The constituents of the naphtha and lighter oils consequently become separated from those of the heavier oils, in and by the operation of the worm E, and the former pass out, thence upward into the discharge-pipe F, which conducts them into the main pipe G, through which they pass into the main condensing-worm H, whose tank I is to be filled with a cold condensing-medium, as usual.

The condensed liquids pass from the worm H into the discharge-pipe J, which conducts them into a suitable receiver for naphtha or lighter oils.

During this operation of distilling and separating naphtha and the lighter oils from the charge, the stop-cock 3 in the pipe G is closed, and the stop-cock 1, in the pipe C, and the stop-cock 2, in the pipe F, are opened.

After all the naphtha and lighter oils have been removed from the charge in the still, I close the stop-cocks 1 2 and open the stop-cock 3, and proceed to distil the remaining portions of the charge, the constituents of the heavier oils passing over in the usual manner, through the pipe or gooseneck C, into the worm and condenser H I, where they are condensed in the ordinary manner, the liquids running off through the same discharge-pipe J, into a different receiver from those which receive the lighter oils, the pipe J being either so made as to be capable of turning in different directions, or being made with suitable branches, having stop-cocks to govern the direction of the flow.

My invention enables me to separate the lighter constituents of the charge from the heavier with facility, without interrupting the process of evaporation, by means of the separating-worm E, and its tank D, and pipes C and F, arranged and combined to operate in conjunction with the still and main condenser, as above described and explained.

What I claim as new, and desire to secure by Letters Patent, is—

The pipe G, with its stop-cock 3, in combination with the pipe C, ascending worm E, pipe F, and condenser H I, all constructed and operating substantially as herein shown and described.

This specification of my invention signed by me, this 23d day of July, 1869.

A. H. TAIT.
